(Cl. D22—3)

FIG. 1

FIG. 3

FIG. 1 is a side elevational view of a knife or similar article showing my new design.

FIG. 2 is an edge view as seen from the right of FIG. 1.

FIG. 3 is another side elevational view showing the side opposite to that seen in FIG. 1.

The dominant features of my design reside in the handle portion which presents a concave profile in both plan and elevational views all as shown.

I claim:

The ornamental design for a knife or similar article, as shown and described.
